By his Atty. *G. H. Albee*.

UNITED STATES PATENT OFFICE.

GEORGE O. BERGSTROM, OF NEENAH, WISCONSIN, ASSIGNOR TO
BERGSTROM BROTHERS & CO., OF SAME PLACE.

DESIGN FOR A HOT-AIR FURNACE.

SPECIFICATION forming part of Design No. 27,113, dated May 25, 1897.

Application filed November 13, 1896. Serial No. 612,029. Term of patent 14 years.

To all whom it may concern:

Be it known that I, GEORGE O. BERGSTROM, a citizen of the United States, and a resident of Neenah, in the county of Winnebago and 5 State of Wisconsin, have invented a new and original Design for a Hot-Air Furnace, of which the following is a specification.

The leading features of my design relate to certain forms and ornamentations of the furnace-front, of the fire-pot, and radiators which 10 distinguish them from those of other hot-air furnaces, and they are shown in the accompanying drawing, in which a single view in perspective of the furnace is shown.

15 Similar numerals and letters indicate like parts in the drawing.

1 indicates the furnace-front; 2, the clean-out doors; 3, the fire-door; 4, the ash-pit door; 5, the ash-pit; 6, the fuel-receptacle or fire- 20 pot; 7 7', radiators; 8 8' 8", short pipes for connecting the fire-pot to a radiator and the radiators to each other, respectively; 9, a damper-arm; 10, the damper-rod; 11, the smoke-escape pipe.

25 The front 1 consists of a casting having the doors 2, 2, 3, and 4, the ornamental pilasters *m*, and cross-ribs *n* and *o*. The fire-pot consists of an inclosure of greater length than breadth or height, its top *a* being of a plain 30 oval shape longitudinally and its sides *d* an oval of a lesser degree. The sides are ornamented with the vertical corrugations *e* over their entire length.

The radiators 7 7' are similar one to the 35 other, excepting in their fuel-receiving and smoke-discharge openings, and they are of greater length than breadth or thickness,

each having an open space *g* extending through them in the direction of said thickness, whereby for a greater portion of their 40 length they are divided into two flues, which are circular upon their outer and angular upon their inner sides, they being merged into one flue at the ends of the radiator. Their ends are contracted in width slightly, 45 their forward ends being connected with the furnace-front opposite their respective doors 2. The radiators are formed of two sections, said sections meeting upon a horizontal plane which divides them into equal parts *h* and *i*, 50 which are secured together with the bolts at *f*, their meeting edges forming the rib *j*, which surrounds the radiator upon its sides and rear end and around the space *g*.

The radiators are connected with the fire-pot and with each other by means of the pipes 8, 8', and 8", the latter being provided with a damper 9 and rod 10 for its operation in front of the furnace.

The rear end *b* of the fire-pot extends back 60 a short distance beyond the sides of the fire-pot, forming thereby a pocket at the rear of the fire-pot, in which the smoke and gases will circulate during the combustion of the fuel.

Having described my invention, what I 65 claim, and desire to secure by Letters Patent, is—

The design for a hot-air furnace, substantially as shown and described.

GEORGE O. BERGSTROM.
